UNITED STATES PATENT OFFICE.

WALTER S. ELY, OF FLUSHING, NEW YORK, ASSIGNOR TO REVOLVING-DOOR AND FIXTURE COMPANY, OF NEW YORK, N. Y., A CORPORATION OF NEW YORK.

REVOLVING DOOR WITH CLOSING DEVICES AND PACKINGS.

1,084,204.

Specification of Letters Patent.

Patented Jan. 13, 1914.

Application filed November 22, 1912. Serial No. 732,815.

To all whom it may concern:

Be it known that I, WALTER S. ELY, a citizen of the United States, residing at 18 Ash street, Flushing, borough of Queens, 5 and State of New York, have invented certain new and useful Improvements in Revolving Doors with Closing Devices and Packings, fully described and represented in the following specification and the accompanying drawings, forming a part of 10 the same.

The present invention relates to the revolving doors which are often applied to the entrance of a building to exclude wind 15 and dust; and the object of the invention is to avoid the necessity of providing folding gates or sliding doors in addition to such revolving door, for closing and barring the passageway therethrough. This object 20 is attained in the present invention by forming the curved walls of the casing against which the door-wings revolve, so that the whole or a part of such walls may be slid bodily across the passageway and thus bar 25 the same.

The segments of the casing-walls which are movable across the passageway may be suspended from the roof and supported thereon in moving from one position to the 30 other; or guides may be provided upon the floor or roof and the segments provided with rolls or wheels to ease their movement in such guides. The entire casing-wall may be moved around the center of the casing to 35 close the doorway, or only segmental portions of the two side-walls may be made movable, sufficient to close the doorway when moved together, across the same.

The movable segments are, in practice, 40 formed with locking-bolts or other means, by which they may be secured in their normal position at the sides of the passageway, or in their position across the same so as to wholly bar the doorway.

45 The invention will be understood by reference to the annexed drawing, in which—

Figure 1 is a plan of the roof of a revolving door with the track removed over one of the casing-walls, which is adjusted at 50 the side of the passageway, the other casing-wall being shown in its closed or shifted position; Fig. 2 is an elevation of the revolving door-casing viewed from the direction of the arrow 8 in Fig. 1, with the cornice

omitted, and the casing-wall at the right 55 side moved to its closed position, and the roof shown in section on line 2—2 in Fig. 2; Fig. 3 is a plan of a revolving door with the roof of the casing removed and the entire casing-walls movable; Fig. 4 is a similar 60 plan with only half of each casing-wall movable to close the passageway; Fig. 6 is a section near the edge of the movable wall on line 5—5 in Fig. 5, the view being broken for want of room upon the drawing; Fig. 5 65 is a longitudinal section on line 6—6 in Fig. 6.

In Figs. 1 and 3, a partition or exterior wall A is shown having a passageway therethrough to which the casing of the revolving 70 door is fitted movably.

In Fig. 3, the casing-walls a , a' are of the usual segmental form, the wall-segment a being shown in its normal position at the side of the passageway, and the entire wall-segment a' moved so that its forward edge extends half way across the entrance to the door; so that when the wall-segment a is similarly moved the entrance to the door 75 would be wholly closed. When the forward 80 edges of the segments are thus arranged their rear edges are adjacent to the partition A and thus prevent access to the passageway.

The passageway through the wall A in 85 Fig. 3 equals the diameter of the casing so that it cannot be closed without moving the entire quadrant segments a and a' ; but Fig. 4 shows a wall B with the casing set inside the same, so that the passageway C may 90 equal one-quarter the periphery of the casing, and be readily closed by partial segments of the side-walls.

The casing-walls, which are usually quadrant, may therefore be divided each into 95 two equal segments, the rear segments a^2 being fixed stationary, and thus aiding to support the roof of the casing; while the front segments a^3 are adapted to slide forwardly into contact with one another, as 100 shown in Fig. 4, and close the passageway C.

A box b , containing a yielding packing b' is shown upon the partition-wall B at the edges of the passageway C, to engage the forward edge of each segment a^3 when in 105 its normal position, and their rear edges when in their closed position, to exclude air when the doorway is closed.

With both the constructions shown in Figs. 3 and 4, the door-wings *c* which are carried by a central post *d*, revolve with their edges not far from the edges of the opening in the exterior wall, and the casing-segments are movable between the edges of the door-wings and the edges of the said opening, so that they may be slid across the opening when required.

- 10 Means are provided upon the roof of the casing to guide the wall-segments when moved, the roof *D* being formed with a segmental slot *f* through which hangers *e* are extended from the tops of the wall-segments and thus guide the upper ends of the segments. A curved bar *g* is shown attached to the floor and fitted to a groove in the bottom of each of the wall-segments to guide their lower ends. A track *f'* is provided upon the 15 roof above the slot *f*, to which track-wheels on the hangers are fitted, and the wall-segments are thus hung and sustained movably upon the roof.

Where the entire wall-segments are movable, the roof is necessarily supported and braced by suitable means which are not shown herein, as they vary with each installation. The walls are also held from displacement in either position by locking-bolts *h* and *h'* projected from the upper and lower ends of the movable segment into the roof and floor respectively.

Holes *i* are shown in the floor in Figs. 3 and 4, and holes *j* in the roof; and Figs. 3 and 4 show the bolts *h* in the upper ends of the wings, which are adapted to fit the holes *j* in the roof to secure the movable segments in either position.

Figs. 5 and 6 show the bolts fitted within the body of the segment and a crank-plate *k* sunk in the segment flush with its surface and connected with the bolts *h* and *h'* by pin and eye-connections *l* and *l'*. A pinion, engaging racks upon the bolts, or any other rotary bolt-mover, may be used instead of the crank-plate *k*. The crank-plate *k* is journaled in a metallic housing *m* and has a square or polygonal socket *m'* upon its inner side only, into which a wrench of suitable form can be fitted to turn the crank-plate and throw the bolts into their respective holes. With this construction, the locks upon the two segments are inaccessible from the outer side when the doorway is closed, and the fixtures are flush upon the inner sides of the segments so as not to interfere with the rotating wings. The mere shifting of the bolts permits the segmental walls to be moved into either required position, and 60 locked securely therein.

Where the side-walls of the casing are movable across the passageway as shown herein, they cannot be held so rigidly as if permanently fixed at the sides of the door-wings, and are thus liable to be a little out

of plumb or concentricity with the spindle of the wings, for which reason it is desirable to furnish a packing for the edges of the door-wings which will compensate for any inequalities in the surface of the casing-walls, and this is provided by the sectional packing shown herein.

It is obvious that where access from the exterior of the building is desired through the revolving door after the segments are locked across the passageway, a lock must be used as upon ordinary doors, having a key-hole upon the outer side by which the bolts upon one or both of the segments may be moved to permit the opening of the same.

It is obviously immaterial what form of lock be employed to secure the segments in their opened or closed position, and a mere hook and eye to engage the two segments with one another would suffice if a stop were provided upon the roof of the casing, as shown at *w* in Fig. 2, adapted to arrest both the segments when moved to their closed position.

Having thus set forth the nature of the invention what is claimed herein is:

1. The combination, with a wall having a passageway therethrough, of a revolving door having radial rotatable wings to exclude dust and wind, a casing having wall-segments operating in a fixed position at opposite sides of the passageway in coöperation with the rotatable wings when passengers are moving through the same, and movable into a fixed position across the passageway when required to close the same.

2. The combination, with a wall having a passageway therethrough, of a revolving door having radial rotatable wings to exclude dust and wind, a casing having wall-segments operating in a fixed position at opposite sides of the passageway in coöperation with the rotatable wings, and movable across the passageway to close the same, and means for securing such segments across the passageway to bar passage therethrough.

3. The combination, with a wall having a passageway therethrough, of a revolving door having radial rotatable wings to exclude dust and wind, casing-walls formed each in two segments arranged in a fixed position at opposite sides of the passageway when the door is in use, and detachable segments of such walls movable across the passageway to close the same, and provided with means for securing them in such closed position to bar the passage through the passageway.

4. The combination, with a wall having a passageway therethrough, of a revolving door having radial rotatable wings to exclude dust and wind, a stationary roof supported above the wings to sustain a bearing therefor, wall-segments operating in a fixed position between the floor and said roof at

opposite sides of the passageway in coöperation with the rotatable wings when passengers are moving through the door, and means for sustaining the wall-segments
5 movable upon the roof whereby they may be turned across the passageway to close or bar the same.

In testimony whereof I have hereunto set my hand in the presence of two subscribing witnesses.

WALTER S. ELY.
